UNITED STATES PATENT OFFICE.

CHARLES M. COTT, OF COLUMBUS, OHIO.

LOOSE-LEAF BINDER.

No. 925,869.

Specification of Letters Patent. Patented June 22, 1909.

Application filed November 23, 1908. Serial No. 464,112.

To all whom it may concern:

Be it known that I, CHARLES M. COTT, a citizen of the United States, residing at Columbus, in the county of Franklin and State of Ohio, have invented certain new and useful Improvements in Loose-Leaf Binders, of which the following is a specification.

My invention relates to the improvement of loose leaf binders or covers for books of that class in which sheets of paper are removably bound, and the objects of my invention are to provide a simple and improved construction of loose leaf binder; to provide an improved hinge construction between the book back and cover boards; to provide improved binding means by means of which the removal or insertion of pages or sheets may be readily and easily effected; to provide means for locking or permanently binding the leaves of the book whereby they may be retained in a bound condition independent of the book cover, and to produce other improvements in details of construction which will be more fully pointed out hereinafter.

These objects I accomplish in the manner illustrated in the accompanying drawing, in which:

Figure 1 is a view in perspective of one of my improved binders, showing for the sake of illustration, a portion of the bound sheets broken away, Fig. 2 is a sectional view through the book back, the same being taken through one of the binding bars, Fig. 3 is a detail view in perspective of one of the hinge plates, Fig. 4 is a similar view of one of the removable hinge rods, and, Fig. 5 is a similar view of one of the binder bars.

Similar numerals refer to similar parts throughout the several views.

In carrying out my invention, I employ upper and lower cover boards 1 and 2 and a uniting curved back 3. This latter is made rigid, by the employment therein of a plurality of curved and united back sections, one of which as indicated at 3^a is comparatively thick and of material rendering it non-bendable. The rigid back thus formed, comprises also, strips of flexible material 4 and 5, the end extensions of which form flexible connections with the cover boards 1 and 2, by being securely united therewith or embedded therein in the manner indicated in Fig. 2 of the drawing. I also employ in making each of these connections, an inner

flexible connecting strip 6 which has its outer end portions united to the inner faces or surfaces of the cover boards and which forms an inner lining for the back 3. The back 3 is further reinforced by a curved strip 7, which is on the outer side of the strip 4, said strip 7 being covered by an exterior facing 8 of leather or suitable material, which is also extended to cover the outer surfaces of the back boards 1 and 2. On the inner side of the inner flexible strip 6 between the upper portion of the cover back 3 and the upper cover board, I provide and secure a transverse metallic hinge plate 9, a similar plate 10 being employed and secured against the inner surface of the strip 6 between the lower edge of the cover back and the rear end of the cover board 2. Each of these strips, which is of substantially equal length with the cover back and which runs parallel therewith, consists, as shown more clearly in Fig. 3 of the drawing, of a metallic plate or strip doubled upon itself, being formed at its doubling line with a tubular edge or margin, as shown at 9^a. At desirable intervals this tubular plate edge is provided with vertical recesses, as shown as 9^b.

In each of the upper and lower portions of the flexible connections of the back and cover boards, I employ a metallic binding strip 11, the latter being arranged parallel with the corresponding hinge strip and on the outer side of the strip 4. These binding strips 11 are rigidly connected with the plates 9 and 10 through the medium of rivets 12 and serve to bind the strips 4, 5 and 6 into close engagement with each other. The tubular portions 9^a of the plates 9 and 10, are when the cover boards are closed toward each other, adjacent to or form abutments for the rear or inner ends of said cover boards.

13 represent binding bars or posts, each of which is in the nature of an elongated bar and is provided in each end with an opening 14 in the direction of the width of the bar. These binder bars are adapted, as shown in the drawing, to have their ends inserted in the recesses 9^b of the plates 9 and 10 in which position they are locked by means of detachable rods 15 which, as shown, are adapted to be inserted in the tubular marginal portions 9^a of the plates and to pass through the openings 14 of said bars 13. As will be observed by reference to Fig. 3 of the drawing, the passage through the tubular portion 9^a of each of the plates 9 and 10 is closed at one

end and the pins 15 when inserted in said passages for temporary binding purposes, terminate short of the closed ends thereof. It will be understood, however, that the 5 leaves 16 which are to be bound within the book cover, are formed in their rear marginal portions with openings 17 which are adapted to receive the bars 13, the insertion of the latter being accomplished when one of the rods 15 is pulled outward and one end of 10 each of the bars 13 is thus detached from one of the hinge plates. In constructing each of the pins 15, I form one of the ends thereof pointed and the remaining end portion is 15 provided with screw threads, to admit of the employment of a detachable internally threaded button or finger piece 15^a.

By the means shown and described, it will be understood that all, a portion, or one of 20 the sheets 16 may be removed from the binder or inserted therein by the withdrawal of one of the rods 15 and that a comparatively small number of leaves may be inclosed in the binder, or a sufficient number to fill the space 25 between the tubular portions of the hinge plates.

In case the book has been filled or completed, or for any other cause, it is desired to discontinue the use of the book, or to discontinue 30 the adding of leaves thereto, or removal of leaves therefrom, it is obvious that the binding may be made substantially permanent by the removal of the threaded caps or finger pieces 15^a from the rods 15 and by 35 then forcing said rods inward to their limit of movement within the tubular portions 9^a of the plates 9, in which position the outer end of each of said rods will be inaccessible and the binding will thus become permanent.

40 It will be observed that the plates 9 and 10, serve the double purpose of binding to-

gether the flexible extensions of the cover back and of forming hinge members between the back and cover boards. By securing the hinge plates to the flexible connection, the 45 rigid back section and the hinge plates are permanently united and if through constant use, the cover boards become broken or torn away, the binding action is in no wise impaired and the back section which ordinarily 50 contains the identifying data of the volume, is retained in position.

What I claim, is:

1. In a loose leaf binder, the combination with a rigid back and rigid cover boards, and 55 a flexible connection between said back and cover boards, of hinge plates united to said flexible connections, each of said hinge plates comprising a recessed tubular marginal portion closed at one end, binding bars adapted 60 to connect the recessed portions of said binding plates, detachable rods for connecting said hinge plates and binding bars, and a detachable head threaded upon each of said rods. 65

2. In a loose leaf binder, the combination with a rigid back section, of rigid cover boards, flexible fabric connections between said back and cover boards, hinge plates secured to and carried entirely by said fabric 70 connections, binding bars adapted to connect said hinge plates, and removable rods for connecting said binding bars and hinge plates, said flexible connections serving as hinges for the cover boards. 75

In testimony whereof I affix my signature in presence of two witnesses.

CHARLES M. COTT.
